US00D925287S

(12) **United States Design Patent** (10) **Patent No.:** **US D925,287 S**
(45) **Date of Patent:** ** *Jul. 20, 2021

(54) **BEVERAGE CONTAINER**

(71) Applicant: **Leapfrog Product Development LLC**, Chicago, IL (US)

(72) Inventors: **Glen C. Gilmore, III**, Naperville, IL (US); **Micaela K. McCabe**, Chicago, IL (US); **Steven N. Pinelli**, Ogden Dunes, IN (US); **Derek J. Leatzow**, Chicago, IL (US); **Brian M. Clemens**, Burnsville, MN (US); **Richard E. Ellison**, Chicago, IL (US); **Kurtis M. Sward**, Anna Maria, FL (US)

(73) Assignee: **Leapfrog Product Development LLC**, Chicago, IL (US)

(*) Notice: This patent is subject to a terminal disclaimer.

(**) Term: **15 Years**

(21) Appl. No.: **29/682,581**

(22) Filed: **Mar. 6, 2019**

(57) **CLAIM**

We claim the ornamental design for a beverage container, as shown and described.

DESCRIPTION

FIG. 1 is a top perspective view of the beverage container according to the new design.

FIG. 2 is a bottom perspective view of the beverage container shown in FIG. 1.

FIG. 3 is a front elevation view of the beverage container shown in FIG. 1.

FIG. 4 is a rear elevation view of the beverage container shown in FIG. 1.

FIG. 5 is a left side elevation view of the beverage container shown in FIG. 1.

FIG. 6 is a right side elevation view of the beverage container shown in FIG. 1.

FIG. 7 is a top plan view of the beverage container shown in FIG. 1; and,

FIG. 8 is a bottom plan view of the beverage container shown in FIG. 1.

1 Claim, 8 Drawing Sheets
